UNITED STATES PATENT OFFICE.

GEORGE L. WALL, OF LIMA, OHIO, ASSIGNOR TO LIMA LOCOMOTIVE CORPORATION, OF LIMA, OHIO, A CORPORATION OF OHIO.

CAST-STEEL VESTIBULE-FRAME.

1,138,028.

Specification of Letters Patent.

Patented May 4, 1915.

Application filed December 19, 1914. Serial No. 878,018.

To all whom it may concern:

Be it known that I, GEORGE L. WALL, a citizen of the United States, residing at 1103 West High street, Lima, county of 5 Allen, and State of Ohio, have invented certain new and useful Improvements in Cast-Steel Vestibule-Frames, fully described and represented in the following specification and the accompanying drawings, forming a 10 part of the same.

This invention relates to an improved vestibule attachment for application to the end of a tender, a tank-car, or any car-body having a closed end, and the object of the invention is to furnish a construction of cast-steel in as few parts as possible, so as to 15 simplify the construction of the vestibule, its handling in the manufactory, and also to facilitate its application to or removal 20 from the end of a car. To effect this object, the vestibule-frame is formed with two side-plates of cast-steel in one piece with cross-bars connected to the same, and with flanges for connecting the foot and top of the vestibule to the car. This one-piece structure is, 25 when applied to the end of a tank upon a tender or tank-car, supported at the lower end by connection to the end-sill, and at the upper end by brackets attached to the top 30 of the tank. Heretofore, the frame of such vestibules has been made of separate parts secured together, and the manufacture of such a vestibule-frame in one piece of cast-steel cheapens the construction and reduces 35 the cost of securing it to the end of the car.

The side-plates of the cast-steel frame are made with upright flanges at their inner edges to bear upon the end of the car-body, tender or tank; and with flanges at their 40 outer edges to oppose the rubbing-plate which is supported yieldingly upon the outer edge of such a vestibule-frame. Integral cross-ties connect the inner edges of the side-plates, and may be constructed to 45 bear upon the end of the car-body or tender, but the flanges upon the outer edges of the side-bars (which project beyond the end sill of the car or tender) are preferably connected with an integral cross-bar at the top 50 only, and the flanges upon such outer edges may also be connected by separate auxiliary ties bolted at their ends thereto. Such construction facilitates the casting of the integral parts in one piece.

55 As this integral cast-steel vestibule-frame

is adapted for attachment to various kinds of cars, including a tank-car and a locomotive tender, I have used the term "car" in a general sense in the claims appended hereto.

The invention will be understood by reference to the annexed drawing, in which—

Figure 1 is an end view of a car-frame and tank with the vestibule upon the end of the same; Fig. 2 is a side view of one end of the car-frame and tank with the vestibule thereon; Fig. 3 is a plan partly in section, of the parts shown in Fig. 2; and Fig. 4 is a plan of a locomotive-tender and the end of an adjacent passenger-car, with a vestibule attachment upon the tender.

In Figs. 1 to 3, A designates the sides of the car-frame, and B its end-sill.

A cylindrical tank C with convex end C' is shown supported upon the end sill by lugs D, and the top of the tank is shown provided with two parallel brackets E which extend a little beyond the corner of the convex tank-head C'. The side-plates F of the vestibule-frame are shown extended from the sill B to the top of the brackets E, and each is provided with a curved upright flange F' to bear against the curved head of the tank, and near the top with vertical flanges G' which are fitted to flanges D' upon the outer ends of the brackets, and are bolted thereto. 80 The vestibule is thus supported by its upper and lower ends. Cross-bars H are formed integral with the side-plates intermediate to the top and bottom, and curved to bear against the convex end of the head C'. The 85 outer edges of the side-plates are formed with flanges F² which are united at the top by an integral cross-bar F³, and at the bottom by a detachable tie B'. The lower ends of the side-plates are provided with transverse feet F⁴ to fit against the end sill B, to 90 be bolted thereto. The flanges F² project beyond the outer side of the sill to support the rubbing-plate I, which is in practice mounted yieldingly upon the flanges F², but 95 the yielding connections of the rubbing-plate are not shown, as such plate forms no part of the present invention.

The parts lettered F to F⁴ inclusive are all formed in one piece by casting of steel, 105 and form my improved vestibule-frame.

By the use of the brackets E upon the top of the tank and the connection of the vestibule-frame thereto and to the sill near the bottom of the tank, such frame is fully 110

supported without bolting to the head C' of the tank, which would involve great risk of leakage; but the contact of the flanges F' with the head of the tank relieves the connections of all strain in case of collision. The brackets E are secured upon the top of the tank in a line with the side-plates F of the vestibule, and a sheet-metal roof-plate J is shown extended over the tops of the brackets and the tops of the vestibule side-plates to the outer cross-bar F³, thus forming a hood which wholly covers the top of the vestibule-frame. Such a hood wholly incloses the interior of the vestibule and shuts off tramps, train-thieves, &c. from access to any car connected therewith.

Fig. 4 shows in plan the vestibule-frame applied to the flat rear end of a locomotive tender M, and its rubbing-plate I' fitted 20 against that of a vestibule K upon the end of a passenger-car L.

Where the vestibule-frame is fitted against a flat surface like the rear end of a tender, the flanges F' are necessarily made vertical 25 to contact with the end of the tender-tank; but the frame is held in place entirely by bolting to the rear sill of the tender and to the rear ends of brackets D upon the top of the same, as already described. Such a vertical disposition of the inner edge of the vestibule-plates adapts them to bear against 30 the closed end of a car-body as well as the rear end of a tender.

Where attached to the end of a passenger-car, the vestibule-frame cannot be connected to the car-body intermediate to its upper and lower ends without obstructing the passageway through the vestibule, and it is equally true, in the application of a vestibule to the rear end of a locomotive-tender, that it is undesirable to connect the vestibule-frame to the same at any points except its ends; as the jarring of the vestibule-frame would produce leaks if riveted to the 45 tender-tank.

My vestibule-frame is therefore formed at the bottom with means for attaching it rigidly to the end sill of the car, and at the top with means for attaching it to a bracket 50 secured upon the top of the tank, where leak-

age could not occur. It can thus be removed at any time by merely detaching the boltings.

From the above description it will be understood that the invention comprises a vestibule-frame which is complete in itself, and does not require to be built piecemeal upon the car; and when secured upon the end of a tank, car-body or tender, is adapted to carry the rubbing-plate and to transmit any shock to the vestibule-frame upon an adjacent car, and it can also be removed bodily from the car whenever required, by detachment from the brackets D.

Having thus set forth the nature of the invention what is claimed herein is:

1. A vestibule attachment for a car having a tank, consisting of a unitary casting having side-plates projected from the tank beyond the end of the car-frame, with upright flanges upon the inner edges of the side-plates to fit against said tank and having integral cross-bars connecting the side-plates, means for attaching the foot of the vestibule casting to the end sill of the car, and side brackets upon the top of the tank 75 with connection from the outer ends of the same to the inner edges of the side-frames, whereby the entire vestibule is supported at the top and bottom only, and the side-plates of the vestibule are disconnected from the rear end of the tank.

2. A vestibule attachment for a tank-car or tender, consisting of a unitary casting having side-plates provided with upright flanges to bear against the end of the car-tank, integral cross-bars connecting the inner edges of the side-plates, detachable ties connecting the outer edges of the side-plates, means at the foot for attachment to the end sill of the car, and means at the top for connection to brackets upon the tank, substantially as and for the purpose set forth.

In testimony whereof I have hereunto set my hand in the presence of two subscribing witnesses.

GEORGE L. WALL.
